UNITED STATES PATENT OFFICE.

JOSEPH H. BACON, OF DETROIT, MICHIGAN, ASSIGNOR OF ONE-HALF TO
JOSEPH H. BERRY, OF SAME PLACE.

SECTIONAL BOILER.

SPECIFICATION forming part of Letters Patent No. 552,861, dated January 7, 1896.

Application filed May 18, 1895. Serial No. 549,809. (No model.)

To all whom it may concern:

Be it known that I, JOSEPH H. BACON, of Detroit, in the county of Wayne and State of Michigan, have invented a new and useful 5 Improvement in Sectional Boilers, of which the following is a specification.

My invention consists in an improvement in sectional boilers or water-heaters, herein-after fully described and claimed.

10 Figure 1 is a perspective view of a complete boiler. Fig. 2 is a side elevation of one section. Fig. 3 is a section on line $x-x$, Fig. 5. Fig. 4 is a section on line $y-y$, Fig. 5. Fig. 5 is a vertical central longitudinal section, and 15 Fig. 6 is a front elevation of the rear section.

My invention relates to that type of boilers or heaters which are made by assembling a series of cast sections, and providing the boilers thus made with a suitable front section having fire and ash-pit doors, and a cleaning-door, if desired, and a closed rear section.

20 F represents one of the main sections, the lower part of which is formed with downwardly-projecting water-legs H H, provided at their lower ends with lugs J to support a grate K, and supported on sectional legs I, which form a base, each leg being fastened to the section which it supports in any convenient way, thus leaving a fire-chamber in 25 each section.

Grate K may be supported on the base if desired.

Above the fire-chamber A the part B of the 30 section corresponding to the crown-sheet of a boiler is made narrower than the side H of the section, except at its center G, where each section is enlarged, as shown in Fig. 4, to the width of the outer side H, so that when a number 35 of these sections are assembled they will come in close contact at their outer edges and at the center of the crown-sheet, as clearly shown in Fig. 4.

e represents a vertical flue in the center of 40 each section above the center G of the crown-sheet, extending from above the crown-sheet to nearly the top of the section.

M M represent water-chambers which extend from the sides of the section to the center flue e, and O O represent vertical pipes

connecting water-chamber M with the crown-sheet portion of the section.

D D represent vertical water-pipes connecting the water-chamber M with a water-chamber m, preferably having an inclined 55 top, the apex of which is formed with an opening L.

The sides H extend above water-chamber m, and also connect with discharge-opening L.

s represents draft-openings below water-chamber M. t represents draft-openings above water-chamber m, and E E represent draft-openings which lead to the back of the boiler and communicate with draft-openings d d, formed on the rear section S, which leads 65 into a pipe g, intended to be connected with a chimney.

P represents a header or manifold, connected with the water-opening L, in each section, as shown in Fig. 5, and from the header 70 P distributing-pipes or leaders lead out to the points desired.

The rear section S consists of a hollow cast box, having a water-chamber f therein, connected at its top with header P, having in its 75 side near the top draft-openings d d, which lead into a single box d on the rear of section S, on which is formed a pipe g.

The front section R consists of a casting which need not be hollow to contain water, 80 though it may be so made if desired, and which has formed in it at the upper part a cleaning-door b, near its center a fire-door c, and at its bottom an ash-pit door h.

N represents a header on each side of the 85 boiler, connected with each section F at the lower part of its water-leg, into which the return or drip pipes lead.

When a boiler made of a number of these sections secured together is filled with water, 90 and a fire is built in the grate K, a very large surface is exposed to the radiant heat of the fire, including the inner sides of H. The crown-sheet B and a large part of the upper portion of the section up to water-chamber 95 M are thinner than the full thickness of the section and also the water-box of the rear section S below the water-chamber M. The products of combustion from the fire pass up between the crown-sheets B of the section, 100

except at the center G, thence pass through the draft-openings S between the pipes O to the center flue e, water-chamber M acting as a baffle-plate, and thence travel both ways through openings t between pipes D to the draft-openings E, thence back through the draft-openings d and out of pipes g. The heated water, or mingled water and steam, rises through water-legs H, pipes O, water-chamber M, and pipes D, and flows out either in the shape of hot water or steam through discharge-openings L in the header P, for distribution in the ordinary manner.

If used as a water-heater, of course the boiler and all pipes connected therewith will be full of water, while if used for steam the water-level will be preferably below the upper side of the water-chamber M, thus giving the whole upper portion of the section as a separator, and permitting a downflow of water on the outside of each section, in addition to the return through header N.

What I claim as my invention, and desire to secure by Letters Patent, is—

1. A section for a sectional boiler made in one piece having divided water legs, a crown sheet adjoining said water legs, and narrower, except at its center, than the water legs, a vertical central flue having a crown sheet, a water chamber acting as a baffle plate on

each side of said flue, and of the full thickness of said section, a water chamber above said baffle plate and vertical pipes connecting the crown sheet portion with said baffle plate and other vertical pipes connecting said baffle plate with the top of the section, substantially as shown and described. 35

2. A section F, in a cast iron boiler, having the sides H, the crown sheet part B, made narrower than the sides except at its center 40 G, a vertical central flue e, a water chamber M on each side of said central flue of the full thickness of the section, to act both as a water chamber and baffle plate, vertical pipes D connecting said water chamber M 45 with the top of the section, draft openings s between pipes O and draft openings t between pipes D, and a draft opening E at the sides of the section above the baffle plate, in combination with a rear section S consisting of 50 a water box, provided with draft openings d to register with draft openings E, all connected with a header P at the top, and provided with a header N at the base, substantially as shown and described.
